UNITED STATES PATENT OFFICE.

HERVEY GAGNÉ, OF ST. JEAN D'IBERVILLE, QUEBEC, CANADA.

LOCKING DEVICE.

Application filed September 5, 1922. Serial No. 536,282.

To all whom it may concern:

Be it known that I, HERVEY GAGNÉ, a subject of the King of Great Britain, residing at St. Jean d'Iberville, Province of Quebec, 5 Canada, have invented certain new and useful Improvements in Locking Devices; and I do hereby declare that the following is a full, clear, and exact description of the invention, such as will enable others skilled 10 in the art to which it appertains to make and use the same.

The present invention relates to a new and useful locking device to be used in connection with railway switches.

15 In railway switches of this character already in existence, it has been found that when the switch rail is shifted into a desired position it often becomes displaced or works itself loose whereby a train may become derailed or directed to the wrong track.

20 With this difficulty in view, the primary object of the invention resides in an attachment associated with a railway switch, whereby the switch rail is positively locked in desired position. Accordingly, it is impossible, with this invention in use, for the switch rail to move out of the adjusted position.

A further object of the invention is the provision of a construction of this nature in 30 which the working parts are protected from the weather and are consequently operable in all seasons.

Further objects of the invention will appear as the description continues, while others will be particularly pointed out. The invention is fully disclosed in the following description and in the accompanying drawings in which:

40 Figure 1 is a side elevation of the device applied to a railway switch;

Fig. 2 is a plan thereof;

Fig. 3 is a detail of the device per se;

45 Figure 4 is a view taken at right angles to Figure 3;

Figure 5 is a section on the line 5—5 of Figure 4;

Figure 6 is a section on the line 6—6 of Figure 5;

50 Figure 7 is a detail of the lock box with the cover removed; and,

Figure 8 is a similar view of a modified form.

55 Referring to the various views by corresponding reference characters throughout, the numeral 10 indicates a railway track

mounted on ties 11 and including a switch rail 12. At one side of the track and in proximity to the switch rail is an operating or shifting device 13 comprising a standard 14 in the top of which is formed a square hole 15. A block 17 having a squared bottom 18 is mounted upon the standard, the squared portion 18 fitting in the recess 15. A shaft 19 passes through the block 17 and through the standard. The lower end of the shaft carries an eccentric device 20 to which is pivoted a link 21 extending to the switch rails 12 and secured thereto.

The shaft 19 is surrounded at its upper 70 end by a fixed collar 22 to the upper end of which is pivoted a lever 23. The latter is fulcrumed at one end of a link 24, this link being pivotally mounted on the block 17, as at 25. A flange 26 surrounds the block and 75 has secured thereto a rod 27 which extends downwardly and carries at its lower end a link 28 connected to a bell crank lever 29 pivoted at the base. At the other end of the bell crank lever is a thimble 29' in which is 80 received the threaded end 30' of a connecting rod 30. The other end of the connecting rod is pivoted as at 30" to a rack 51 extending into the locking device 31, later to be described. A guide member 32 for the rod 27 85 is mounted on the standard, and an oil cup 14' is provided in the base of the standard to afford proper lubrication to the shaft 19.

The locking device, as shown in Figure 7, 90 consists of a box 33 divided into three compartments by the partitions 34, 35. In the lower compartment 36 is mounted a rotatable pulley 37, while a rod 38 is slidable through the partitions.

A cable 39 connected to the lower end of 95 the rod 38 and passing around the pulley has its opposite end connected to the pivot point 30" when this modification of locking device is employed. The other end of the rod 38 is provided with a head 40, and an expansion 100 spring 41 surrounds the portion of the rod between the partition 34 and the head. In the intermediate compartment the rod 38 is provided at its lower surface with teeth 42 between which is a notch 43. A second or 105 auxiliary switch actuating rod 44, similar to the rod 21, is connected to the switch rails and extends into the box 33. The inner end of this rod is provided with notches 45 through which the rod 38 is free to move. 110 When the notch 43 of the rod 38 is superposed over the rod 44, the latter is free to

reciprocate, but when one of the teeth 42 lies in either of the notches 45 the rod 44 is locked.

The operation of this device is as follows: 5 When it is desired to shift the switch rails, the handle or lever 23 is pulled upwardly, whereupon the squared end 18 is freed from the recess 15 and the rod 27 is raised. Thereupon the link 30 is moved towards the standard, and through the action of the bell crank lever 29, the rod 38 is pulled towards the pulley 37 so that the notch 43 overlies the rod 44, as shown in Figure 7, and allows the latter to reciprocate. With the block 17 in 15 raised position, the lever 23 is turned in the horizontal plane, causing reciprocation of the switch actuating rod 21 and the auxiliary rod 44. The lever 23 is now moved downwardly so that the squared end 18 again seats in the recess 15, but in a different 20 position than formerly. The resulting downward movement of the plug allows the expansion spring 41 to draw the rod 38 back into its former position, so that one of the 25 teeth 42 holds the rod 44 against movement, thus locking the switch in the desired position. As further securing means, there is provided on the rotatable block 17 and adjacent the handle 23 an apertured lug 17' 30 adapted to receive a padlock 17" for retaining the handle in lowered position. Similarly the box 33 is provided with a padlock 33' for preventing undue interference with the working parts therein. It will be noted 35 that the main and auxiliary switch actuating rods 21 and 44 respectively are articulated as at the pivot points 21' and 44' to provide greater flexibility.

The preferred form of locking mechanism 40 which is illustrated in Figure 1 is shown in detail in Figure 8. The pulley and cable device of Figure 7 is replaced by a rack 51 adapted to reciprocate through the box and a pinion 50 for cooperation therewith. This 45 pinion is adapted to engage with teeth 52 formed in the rod 38' which corresponds to the rod 38 of Figure 7. The various movements effected at the standard cause reciprocation of the rod 38 and rack 51 through 50 the medium of the pinion 50, as a result of which the locking operation is effected in the notches and teeth 42, 43, 45, as already described in connection with Figure 7, since the arrangement of the latter parts is the same 55 in both cases. The box 31 is maintained in upright position by means of angular braces 53 mounted on the extensions of the ties 11.

Having thus fully described the invention, what I claim as new and desire to protect by Letters Patent is:—

1. A switch locking device comprising a main switch actuating rod adapted for connection with a switch rail, an auxiliary

switch actuating rod adapted for connection with the switch rail and movable therewith, a casing mounted adjacent said track and adapted to slidably receive a portion of the auxiliary rod, and means within said casing for positively locking the auxiliary rod upon shifting of the main rod. 65 70

2. A switch locking device comprising a main switch actuating rod adapted for connection to a switch rail, a standard, a shaft rotatable within said standard and operatively connected with said main rod, an auxiliary switch actuating rod adapted for connection to the switch rail and movable therewith, a portion of said latter rod being toothed, a locking member adapted for co-operation with the teeth of said auxiliary rod, and means for actuating said locking member. 75 80

3. A switch locking device comprising a standard, a shaft supported for reciprocation and rotation within the standard, a main switch actuating rod adapted for connection to a switch rail and operable upon rotation of the shaft, an auxiliary switch rod adapted for connection to the rail and having teeth, a locking member adapted for co-operation with said teeth, and operable upon reciprocation of said shaft. 85 90 95

4. A switch locking device comprising a main switch actuating rod and an auxiliary switch actuating rod adapted for connection to a switch rail and having teeth, a standard mounted adjacent the track, a shaft operable within said standard and operatively connected with said main rod, a toothed member slidable over the teeth of said auxiliary rod and adapted for locking engagement therewith, and a rack and pinion device operable on said standard for actuating said toothed member. 100 105

5. A switch locking device comprising a standard, a shaft adapted for reciprocation and rotation within said standard, a bell crank lever pivoted to said standard and connected with said shaft for movement upon reciprocation with the latter, a main switch actuating rod adapted for connection to the switch rail and to the shaft, an auxiliary switch actuating rod adapted for connection to said switch rail and movable therewith, teeth formed on a portion of said auxiliary rod, a rack associated with said bell crank lever and lying substantially parallel with said auxiliary rod, a toothed member slidably mounted with relation to the teeth of the auxiliary rod and adapted for locking engagement therewith, and a pinion operatively engaging said rack and adapted to actuate said toothed member. 110 115 120

In witness whereof I have hereunto set my hand.

HERVEY GAGNE.
